A. F. GARCIA

BEET TOPPER

Filed Oct. 8, 1925

Patented Mar. 23, 1926.

1,577,742

UNITED STATES PATENT OFFICE.

ABILIO F. GARCIA, OF SANTA CLARA, CALIFORNIA.

BEET TOPPER.

Application filed October 8, 1925, Serial No. 61,206.

To all whom it may concern:

Be it known that I, ABILIO F. GARCIA, a citizen of Portugal, and a resident of Santa Clara, in the county of Santa Clara 5 and State of California, have invented certain new and useful Improvements in Beet Toppers, of which the following is a specification.

It is one object of my invention to provide 10 a beet topper that will effectually remove the beets from the ground and top them with a minimum amount of manual labor.

It is another object of my invention to provide a vehicle that will effectually extract 15 the beets from the ground as it passes thereover and carry them to an elevated table for the topping operation.

It is still another object of my invention to provide an effective means for carrying 20 the beets against a cutting edge or blade and means for holding the beets firmly in position during the topping process.

It is still another object of my invention to provide a cutting mechanism that will 25 handle beets of all sizes.

It is also an object of my invention to provide a beet topper of the character indicated provided with means for regulating 30 the amount of top removed from the beets.

In the drawing:—

Figure 1 is a side elevation of a structure embodying my invention, part broken away.

Figure 2 is a plan view of the same.

Figure 3 is a section on line 3—3 of Figure 1, part broken away.

Figure 4 is a detail elevation of a portion of the structure, showing the belt operating connections.

Referring more particularly to the drawing, 40 1 indicates a supporting frame carried by axle 2 and wheels 3.

The elevator comprises brackets 4 mounted on frame 1 and in which is mounted a shaft 5 driven by a chain and sprocket drive 6 from axle 2, the shaft carrying, in 45 the present instance, spaced sprockets 7.

Pivotedly mounted on shaft 5 is a guide 8 having sides 9 and having a shaft 10 mounted in its lower end, the shaft 10 carrying spaced sprockets 11. Chains 12 are mounted 50 on sprockets 7 and 11 and on an idler 12^a to maintain the proper tension. On these two chains 12—12 are mounted spaced and transversely arranged bars 13, each bar carrying several spaced and curved fingers

14 so that when the mechanism is set in motion by the forward movement of the vehicle the chains will travel upwardly on the guide 8 and the curved fingers will 60 carry the beets picked up by them to and over the upper end of the elevator.

Any means may be used for swinging the elevator about its pivot 5 so as to insert the fingers in the ground or remove them 65 therefrom, such as a link 15 pivoted to the elevator at 16 and to an operating lever 17 pivoted at 17^a.

The frame 1 carries a trough 18 arranged at right angles thereto and so positioned 70 as to receive the beets discharged by elevator 8—9 at one end, a stripper 19 being mounted thereon to insure the freeing of the beets from the carrier.

The cutting mechanism comprises a circular blade 20 mounted underneath the bottom of trough 18 as at 21 and driven by gears 22 and shaft 23, shaft 23 being carried by brackets or hangers 24 and driven by chain and sprocket drive 25 from 80 axle 2.

To secure the proper feeding of the beets to the knife I provide a chain 26 carrying fingers 27 and mounted on three sprockets as 28—29—30 mounted on bearings 31—32 85 and 33 respectively and so positioned as to carry the fingers 27 in a plane parallel to the bottom of the trough 18 and close thereto with substantially one-half of the chain outside of the trough as shown. The sprocket 29 is arranged between sprockets 28 and 30 and just above the cutting blade 20.

To hold the beets in position during the cutting process I provide a bar 34 carrying a number of spring elements 34^a and mounted on a spring 34^b which is angularly positioned relative to the side of trough 18 and is secured thereto at one end as shown at 34^c. The other end is bent at substantially right angles as at 34^d and passes through the side of the trough and is fitted with a spring 35 and a nut 36.

To drive the chain and sprocket mechanism described I provide a gear 37 on the lower end of shaft 38 carrying sprocket 30, and this gear is driven by the gear and shaft connections 39—40—41—42 to shaft 23.

It is desirable in a device of this kind that suitable means be provided for regulating the cut. For this purpose I form 110 an opening 43 in the floor of the trough 18,

the cutting blade 20 projecting beyond the forward edge of this opening a distance as shown.

At 44 I show a roller mounted just below 5 and parallel with the rear edge of the opening 43 and having a gear connection 45 with the shaft 46 of gear 28. On this roller is a belt 47 engaging an idler roller 48 carried by notched bars 49 engaging pins 50 on the 10 sides of trough 18. This idler roller is positioned below blade 20 and parallel with the forward edge of opening 43 and may be raised or lowered as desired according to the amount desired to be cut from the beets.

15 In operation the machine is drawn along the beet rows in which the beets have been previously loosened by means of a plow or other suitable device, and the elevator is lowered until the fingers 14 enter the loose 20 ground where they pick up the beets and deposit them in the trough 18.

The operator now picks the beets up one 25 at a time and places them upside down in the claws formed by the fingers 27 and chain 26. Each beet is now drawn forwardly resting 30 on the belt 47, the resilient elements 34^a and their spring mounting holding the beet snugly in the claw 27—26. When the beet engages the blade 20 revolving at high speed the head portion between the blade 20 and belt 47 is cut off, the amount removed being determined by the position of the belt relative to the knife as described.

The various gear and chain connections 35 are, of course, properly proportioned to secure the desired speeds of the various operating elements, and it is also to be understood that changes in form, construction and method of operation may be made within 40 the scope of the appended claims.

I claim:

1. In a beet topper, a table, a cutter element operatively mounted parallel with and in close proximity to the bottom thereof, a 45 belt operatively mounted on the table to move in a plane parallel to the cutter and adjacent thereto, spaced beet engaging elements mounted on said belt and arranged

to support the beets at right angles to the cutter, resilient means mounted in opposed relation to said belt and adjacent to said cutter and adapted to engage the beets carried thereby, and means for operating the belt and cutter in coordinate relation with each other. 50

2. In a beet topper, a table, a beet carrier mounted to move over the bottom of said table in parallel relation thereto and adjacent thereto, said carrier including elements adapted to support the beets in perpendicular relation to the bottom of said table, and a cutter operatively mounted in the path of travel of the beets in said carrier, and means for operating said carrier and cutter in coordinate relation with each other. 60

3. In a beet topper, a table, a carrier belt operatively mounted to travel edgewise thereover in close proximity thereto and carrying beet engaging fingers curving outwardly and forwardly therefrom in the direction of travel of the belt, a cutter operatively mounted in the path of travel of the beets in said carrier, and means for operating said belt and cutter in coordinate relation with each other. 70

4. In combination with a table and beet carrier and cutter mechanism operatively mounted thereon, a resilient element mounted on the table in opposed relation to said carrier, and a plurality of resilient fingers mounted on said element and extending outwardly therefrom to points adjacent to said carrier. 75

5. In a beet topper, a table, a carrier belt operatively mounted to travel edgewise thereover in close proximity thereto and carrying spaced beet engaging fingers curving outwardly therefrom in the direction of travel of the belt, a cutter operatively 80 mounted in the path of travel of the beets in said carrier, and resilient fingers mounted on said table in opposed relation to said belt and extending between said spaced fingers. 85

ABILIO F. GARCIA.
